UNITED STATES PATENT OFFICE.

WILLIAM D. HAINES, OF HADDONFIELD, NEW JERSEY.

FURROWING-MACHINE.

1,333,845.

Specification of Letters Patent. Patented Mar. 16, 1920.

Application filed June 6, 1917. Serial No. 173,156.

To all whom it may concern:

Be it known that I, WILLIAM D. HAINES, a citizen of the United States, residing in Haddonfield, Camden county, State of New Jersey, have invented Furrowing-Machines, of which the following is a specification.

One object of my invention is to improve the detail construction of that class of machines commonly employed for harrowing or for forming furrows for the reception of seed of various kinds, with a view to rendering the various elements more substantial and permitting of their convenient adjustment.

15 A further object of the invention is to provide a machine of the type described with means for adjustably supporting a number of furrow or harrow disks, the arrangement being such as to permit of the convenient removal or replacement of said disks as well as the alteration of their angular positions.

Another object of the invention is to provide an improved device for connecting a harrow or furrowing disk to its supporting structure with a view to permitting of the convenient adjustment of said disk about a substantially vertical axis in order to vary the width of the furrow formed.

I also desire to provide novel means for 30 adjustably mounting the supporting wheels of a furrowing machine or harrow;—the invention contemplating the provision of a novel device for swinging the frame of the machine and with it the furrowing disks 35 about the axis of said wheels with a view to varying the depth of the furrow formed.

These objects and other advantageous ends I secure as hereinafter set forth, reference being had to the accompanying drawings, in 40 which,

Figures 1 and 2 are respectively a side elevation and a plan of a furrowing machine constructed according to my invention;

Fig. 3 is a side elevation partly in section 45 illustrating one of the disk-supporting hangers and its associated parts; and

Fig. 4 is a vertical section through one of the disks and its hub, illustrating the detail construction of the various parts.

50 In the above drawings 1 represents a pair of traction wheels each having on its tread a central, radially projecting flange 2 designed to cut into the earth to prevent side-wise movement of the machine. Said wheels 55 are rotatably mounted upon a fixed axle 3 on which they may be longitudinally ad-

justed and thereafter retained in any given position by collars 4, of which there are a pair for each wheel.

At the ends of said shaft 3 are fixed rearwardly projecting frame members 5 whose rear ends are bolted or riveted to and serve as supports for a pair of angle irons 6 arranged with two of their webs parallel and spaced apart to provide a long transversely 65 extending guide or clamping structure. Also engaging the axle 3 and extending forwardly therefrom is a central bar 7 and two side bars 8 whose front ends are connected to a transversely extending frame member 9, the 70 central bar 7 being also extended to the rear of said axle and having branches 10 whose rear ends are rigidly connected to the angles 6 constituting the guideway.

This rearward extension serves to support 75 a driver's seat 11 and its forward portion 7 has fixed to it an upwardly projecting toothed quadrant 12 to whose lower portion is pivoted a controlling lever 13. The latter carries a latch 14 operated through a link 16 80 from a handle 15 at the upper end of the lever. A cross bar 9 is provided with a pair of eye-bolts 17 engaged by two other eye-bolts 18, mounted on a second transverse bar 19 similar to and parallel with the cross bar 85 9 and a tongue 20 extends forwardly from the central part of this second bar, to which it is braced by inclined members 21. At a suitable point adjacent the rear end of the tongue 20 is an upwardly extending standard 90 or bracket 22 stiffened by a rearwardly and downwardly extending brace 23 which extends to the cross bar 19 and is connected by a link 24 with the lever 13;—the arrangement being such that the swinging of said 95 lever on its pivot causes the frame formed by the members 7, 9, 8, 3, 5 and 6 to turn on the axis of the shaft 3 and thereby raise or lower the furrowing or harrowing disks 25 which are carried by the guide 6.

To obtain this object I connect to said guide 6—6, any desired or suitable number of downwardly extending hangers 26, forming the upper end of each of the latter with a circular portion 40 having on its upper 100 face a series of radial teeth designed to cooperate with and be locked by similar teeth on a washer or pad 27 of wedge shaped section. Each of the hangers may be rigidly connected to the guide 6—6 by means of 105 bolts 28 extending through the slot thereof and are each suspended from a plate 29

whose upper surface is grooved to fit onto the top edges of the parallel upwardly projecting webs of the guide members 6—6.

Obviously when the holding nuts of these bolts 28 are loosened, each of the latter with the plate 29 and the hanger 26, may be moved along the guide 6—6 to any position and thereafter said hanger may be turned about the bolt as an axis so as to set its disk 30 in a plane at any desired angle to the line of movement of the machine. For connecting the disks to their hangers, I provide each of them with a central hub or boss in which is cast a central spindle 30 projecting from approximately half its length beyond the convex face of said disk. Said boss or hub is counter-bored concentrically with this spindle for the reception of one end of a sleeve 31 formed with a projecting lug 32 designed to fit between the flanges of the channel shaped hanger 26 to which it may be rigidly connected by a bolt 33. The spindle 30 is held in the sleeve 31 by a pin 34.

In addition to the above parts I provide a laterally extending marking arm 35 connected to the base of the standard 22 by a horizontally extending pivot bolt 36 which will permit of its being projected horizontally at either side of the machine and swung in a vertical plane from one side to the other. This bar is braced to the tongue by a link 37, so connected as to permit of the above noted adjustment, and it is preferably provided at its outer end with an extension arm 38, whose outer extremity carries a vertically extending marking finger 39. The latter is preferably adjustable in a clamp so that its projection below or on either side of said arm may be varied at will.

Under conditions of use the traction wheels are set on the axle 3 at any distance apart suitable for operation on a given piece of work and are retained in these positions by the collars 4. If the machine is to be used for furrowing, a suitable number of hangers 26 is connected to the guide 6—6 at the desired distances apart and the disks carried by said hangers are adjusted about their vertical axes or are placed in the parallel positions shown in Fig. 2, to suit them for making furrows of the required width. By means of the lever 13, the frame comprised by the members 5—5 and 6—6, is then swung

up or down about the shaft 3 to cause the disks 25 to make furrows of the desired depth. The arm 35—38 is also swung down to its horizontally extended position so that the marking finger 39 will form a shallow furrow or line on the surface of the earth parallel with and at a definite distance from the furrow formed by the nearest one of the disks 25, thus providing a guide whereby the driver of the machine may properly locate the latter in making the next series of furrows.

It is to be noted that the toothed block interposed between the circular toothed top portion 40 of the hanger 26 and the rear frame members is preferably made wedge-shaped in section so that even though said frame members 5 be normally in an upwardly tilted position, the hanger 26 is retained in a substantially vertical line as it is adjusted about the bolt 28 to turn its disk from the position shown in Fig. 2, into other 75 positions at an angle thereto.

While I have referred to my machine as designed for furrowing and have designated the disks 25 as furrowing elements, it will be understood that the novel features of the 80 frame and hangers may be advantageously employed in machines employing harrow teeth or cultivator blades in place of the convex disks shown and it is intended that the term "furrowing elements" shall be interpreted as including such equivalent devices.

I claim;—

The combination in a furrowing machine of a pair of wheels; a non-rotatable axle extending through said wheels; two pairs of collars adjustably fixed to the axle on opposite sides of each wheel; frame members projecting rearwardly from the axle on the outer sides of the wheels; a pair of spaced angle irons fixed to said frame members and extending parallel to the axle to the rear of the same and beyond said frame members; furrowing elements mounted on the angle irons; a frame structure extending 100 forwardly from the axle; a tongue attached to said frame structure; and a seat on said structure.

In witness whereof I affix my signature.

WM. D. HAINES.
